UNITED STATES PATENT OFFICE

152,772

DESIGN FOR A BEVERAGE DISPENSER

Stephen V. Dawson, Evanston, Ill., assignor to Orange-Crush Company, Chicago, Ill., a corporation of Illinois

Application October 27, 1947, Serial No. 142,152

Term of patent 14 years

(Cl. D2—3)

To all whom it may concern:

Be it known that I, Stephen V. Dawson, a citizen of the United States of America, residing at Evanston, in the county of Cook and State of Illinois, have invented a new, original, and ornamental Design for a Beverage Dispenser, of which the following is a specification, reference being had to the accompanying drawings, forming part thereof.

Fig. 1 is a front perspective view of a beverage dispenser showing my new design; and

Fig. 2 is a side view thereof in perspective.

The side of the beverage dispenser not shown is the same as the side shown, and the back thereof and the portion of the top lying in a horizontal plane are plain surfaces.

I claim:

The ornamental design for a beverage dispenser, as shown and described.

STEPHEN V. DAWSON.
